CLAIM

The ornamental design for a shower/bath seat, as shown and described.

DESCRIPTION

FIG. 1 is a perspective view of a shower/bath seat in one position showing my design;

FIG. 2 is a perspective view thereof in an alternate position;

FIG. 3 is a perspective view thereof in another alternate position;

FIG. 4 is a front elevational view of a shower/bath seat shown in FIG. 1;

FIG. 5 is a side elevational view thereof; and,

FIG. 6 is a top view thereof.
